LOG BARKING MACHINE

Edward V. Prentice, Portland, Oreg.

Application December 28, 1937, Serial No. 182,143

2 Claims. (Cl. 144—208)

My invention relates to log barking machines of the general type wherein a power driven tool is employed to remove the bark from successive areas presented by rotation of the log in combination with longitudinal movement thereof in progressive process.

The principal object of my invention is the provision of means for barking logs while afloat in the storage pond.

A second object is the provision of extreme durability of such a machine by arrangement of the involved momenta and stresses so as to require engaging elements of minimum dimensions and weights affording opportunity to employ relatively great factors of safety.

Other objects and advantages of my invention will be apparent in the following discourse wherein the significance of the reference numerals in the accompanying drawing, details of construction and manner of use of a typical machine embodying my invention, and the particular advantages thereof are explained.

Figure 1 represents a view of the top of the machine and a fragment of a log in process therethrough.

Figure 2 represents a view of the end of the machine and log shown in Figure 1.

Figure 3 represents a view of the side of one of the elements of the machine partially in elevation and partially in section together with fragmentary sections of the supporting structure therefor taken on the line 3 of Figure 1.

Figure 4 represents a section of the cutter-head and associated parts together with a fragmentary section of the log taken on the line 4—4 of Figure 3.

A float comprising the logs 1, 2, 3, 4, and 5, the stringers 6 and 7, and the planking as 8, 9, and 10, secured together, accommodate two log-handling units indicated generally by the letters A and B of identical form, a barking element indicated generally by the letter C, and controls therefor indicated generally by the letters D and E.

The log-handling units A and B each comprise an endless chain 11 guided by two sheaves 12 and 13 and driven by a chain-pulley 14 which in turn is actuated in rotation by a motor 15 through appropriate gearing contained in the case 16. The case 16 is mounted upon a carriage 17 slidable on the rails 18 and 19 by operation of a pneumatic cylinder 20 connected thereto by the piston-rod 21.

The barking element comprises a rotary cutter-head 22 made up of centrally mounted knives 55

as 23 in Figure 3 the cutting edges of which are disposed to form an approximately helical figure, carried upon the shaft 24 journaled in the beams 25 and 26 and driven by the motor 27 through appropriate pulleys 28 and 29 and belts 30 and 31.

The beams 25 and 26 are rigidly related and are mounted pivotally at the approximate balance thereof upon the horizontal shaft 32 integral with the member 33 in turn mounted pivotally at 34 and 35 in the standards 36 and 37 integral with the carriage 38, slideable upon the rails 39 and 40 by operation of the motor 41 driving the screw 42 threaded into the carriage 38.

The position of the cutter-head 22 in vertical adjustment is controlled by the hand lever 44 pivotally mounted upon a stud 45 integral with the member 38, and formed with a crank-arm 46 connected to the beam 24 by the link 47 pivotally joining the same. Two screws 48 and 49 serve to control and secure the adjustment of the cutter-head in lateral inclination to permit of adjustment of the axis of the cutter-head at inclinations from the horizontal suited to particular work.

The precise vertical adjustment of the cutter-head, however, to accurately gage the depth to which the cutter-head penetrates, is effected by means of the two gage-levers 50 and 51 which are pivotally mounted upon the spindle 52 and formed with arcuate portions of radii approximately equal to the radius of the paths of the cutting edges of the cutter-head 22 as illustrated in Figure 3 at 53. It is to be observed that this gaging is independent of the relative elevations of the log in process and the float carrying the machine. In Figure 4 this relationship is particularly illustrated where the gage-lever 50 is shown bearing upon the surface 54 formed by the cutterhead and the gage-lever 51 is shown bearing upon the bark surface 55 ahead of the cut.

The electric motors for the cutter-head and those for the log-handling units are controlled both as to direction and speed by appropriate apparatus represented at D.

Control of the pneumatic cylinders is effected by the valves 56 and 57 which are supplied with compressed air from a pipe 58 and are so designed as to provide for the admission of compressed air to either end of the cylinders and the release of air from the opposite ends at controlled rates.

The essence of the invention resides in the

coacting means consisting in the combination of elements or units described, rather than in the specific forms of the parts of these units shown and described. A log of the type indigenous to the Pacific Coast is of tremendous weight and size and may not be integrally handled except at great expense and hazard. In consequence of this, the machine must be adapted to the log in the form and place where the same may be economically processed instead of attempting to construct machinery of the necessarily Gargantuan size required to withstand the stresses involved in any rapid processing through any machine capable of withstanding the shocks and strains of such prodigious magnitude as are necessarily involved.

Thus the aim in the present endeavor is to provide means for barking the log without removing it from its place of storage in the mill pond. This is accomplished by maneuvering the log to the machine or the machine to the log in a common means of support, namely, the water in which both machine and logs float.

The natural properties of a log besides its enormous size and weight include characteristics of form which must be considered. The log may not be circular in cross section and almost never approaches the circular form. It may not be smooth or straight or have a uniform section or uniform dimensions thereof. It may float higher on one side than another or it may suddenly turn turtle due to a gradual change in the relative value of the metacentric height of the displacement of either center of buoyancy or center of gravity. The bark will vary in thickness. All of these characteristics in simple or complex combinations are factors to be dealt with.

No attempt is made to lift the log from the water or even partially do so. Instead, the log is embraced by a wrap of the chain 59 in the form of an helix as shown and the carriage 60 is retracted by operation of the pneumatic cylinder 61 to draw the chain 59 snugly about the log.

The motor 62 is started and the log begins to revolve in a counter-clockwise direction as viewed in Figure 2, and at the same time is impelled forward toward the cutter-head by virtue of the gradual movement of each of the chain links from the position where they initially contact the log to the point where they pay off to follow through the sheave 63 in the course of the helical movement thereof.

As the log approaches the cutter-head 22, the latter is raised by means of the hand lever 44. The gage-lever 51 is depressed and the pressure on lever 44 is lessened until the cutter-head assembly is supported by the gage-lever 51 upon the bark of the log. The gage-lever 51 is allowed to rise until the operator ascertains that the bark has been penetrated and that the log and the surface thus made by the cutter-head have passed well under the gage-lever 50 which is now brought to bear upon the newly cut surface and the gage-lever 51 is released. By holding the gage-lever 50 at its normal position the cutter-head will continue to cut down to the surface thus established, or deeper if desired by allowing the gage-lever 50 to rise slightly.

As the end of the log reaches the position of the unit A, the machinery is stopped and a wrap of the chain 11 is thrown around the log in contact with the surface formed by the cutterhead 22. The carriage 17 is retracted by operation of the pneumatic cylinder 20 under control of the

valve 57 until the chain 11 is snugly in place. The motors are again set in operation and the bark-stripping process as described continued until the entire log has been cleaned of bark.

Now it will be observed that the cutter-head will, under guidance of the gage-levers, rise and fall to conform to the elevations of the successive portions of the log presented, and the depth to which the cutter-head penetrates is under constant and instant control so that irregularities in bark thickness and contour of the log surface may be followed with such exactness as may be desired.

Actual surfacing of the log may be controlled by means of the tilting screws 48 and 49 which allow of adjusting the inclination of the cutter-head axis to the exact relationship to the taper of the log required for smooth cutting.

In the embodiment shown, the chains 11 and 59 are driven by electric motors with suitable controls thus allowing of a difference in the actual speed of travel of the two chains to compensate for differences in diameter of the log at the respective places of application of the chains.

However, identical longitudinal urge of the log is provided by the two chains because the two sheaves 12 and 64 may be adjusted as to distance from the respective cooperating sheaves 13 and 63 to exact identity or some different distances to provide such strain between the two feeding devices as will firmly control the longitudinal movement of the log.

The invention, therefore, resides in the special combination of elements adapted in relative adjustment to the log to which every member of the coacting combination is independently adjustable, yet cooperative. Specifically, the two chains may be adjusted to operative lengths suited to the particular portions of the log engaged and are by inherent nature conformable to the irregular shape of the log, yet will cooperatively rotate, feed, and control the log though different lengths of chain are required and different rates of travel thereof necessitated.

The cutter-head likewise adapts itself by means of the controls and adjustments described, to all manner of shapes, diameters, and irregularities cooperatively fed thereto by the chains.

All of the adjustments are flexible while in operation and are so provided for as to allow of simple operation so that the apparatus, itself, is peculiarly adapted to a specific method of barking the log which in itself is novel and rendered practicable by the apparatus described.

Having described my invention, what I claim is:

1. Log barking apparatus comprising, a float, a vertically adjustable cutter-head mounted on said float, and a power driven chain mounted on said float and extending therefrom to make helical contact with a log to be barked to feed the surface of the latter into progressive engagement with said cutter-head in a helical path while said log floats in the water alongside said float.

2. Log barking apparatus comprising, a float, power driven feed units disposed in spaced relationship on said float, chains driven by said feeding units and extending from said float for helical wrapping about a log while said log floats in the water alongside said float, and vertically adjustable cutter-head means mounted on said float medially of said log feeding units.
